ferred. The flap would be on the same sheet but would be bent with the sheets in the opposite direction.

When the recipient receives the letter-form, he reads it and tearing off the sheet containing pages 15, 16, and 17, 18, along line 19 and after making his response on this sheet, folds it up into the form shown in Figure 5 and Figure 8 and cements the flap 21 in place, and then mails it to the originator.

The invention is readily understood by the user and receiver, so that it affords an effective means of correspondence by mail. The last form of the blank when returned is closed so as to be partially confidential, and no clips are necessary. While a glued flap is provided, it is not used when the originator sends it through the mails for its first mailing. No clip is necessary when the letter-form is primarily sent. The drawings indicate in outline a type of printing and reading matter to be applied, as well as the details required to meet postal requirements, and whether such would have prepaid postage or not. It is believed that such details will be evident without further description, and for that reason are not more fully outlined herein. The form used is suitable for the production and distribution of literature, and since the return section is inside the letter-form when originally sent, it is protected from postmarks or other objectionable contacts.

While but two general forms of the invention are shown in the drawings and described in the specifications it is not desired to limit this application for patent to his particular form or in any other way otherwise than limited by the scope thereof, as it is appreciated that other forms could be made that would use the same principles and come within the scope of the appended claim.

Having thus described the invention, what is claimed is:

A letter sheet divided by a central vertical per-

forated line into two main sections, the said sections being divided by a medial crease fold line, each of said main sections providing two extensive spaces, one space on one of said sections bearing the name and address of the addressee and the cooperative space of said last specified section bearing written information thereon, one space of the other of said sections bearing the name and address of the sender and the cooperative space of said last specified section being provided for the addressee's reply, and a flap forming an extension of the section having the sender's address, said flap extending beyond the space bearing the sender's address and said flap having adhesive on one face thereof, the main sections when folded about the aforesaid central vertical perforated line with the aforementioned indicia facing outwardly, and then folded inwardly upon the aforesaid medial crease fold line, providing a pair of outer sheets and a pair of inner sheets, one of said inner sheets having the said flap in outstanding position, said flap when folded about the other inner sheet preventing its unfolding, and when the sheet is divided, said flap being folded and secured to the section for the addressee's reply.
